(57) CLAIM

We claim the ornamental design for a chair for stairlifts, as shown and described.

DESCRIPTION

FIG. 1 is a perspective view of a chair for stairlifts showing our new design;

FIG. 2 is a front view of the same;

FIG. 3 is a back view of the same;

FIG. 4 is a right side view of the same;

FIG. 5 is a left side view of the same;

FIG. 6 is a top view of the same;

FIG. 7 is a bottom view of same; and,

FIG. 8 is a bottom view thereof, the unclaimed environmental structure removed for ease of illustration.

The broken line showing is included for the purpose of illustrating environment and forms no part of the claimed design.
